A. D. CONVERSE.
METHOD OF MAKING HEADS FOR DRUMS AND OTHER MUSICAL INSTRUMENTS.
APPLICATION FILED JUNE 2, 1916.

1,221,141.

Patented Apr. 3, 1917

UNITED STATES PATENT OFFICE.

ATHERTON D. CONVERSE, OF WINCHENDON, MASSACHUSETTS.

METHOD OF MAKING HEADS FOR DRUMS AND OTHER MUSICAL INSTRUMENTS.

1,221,141.

Specification of Letters Patent.

Patented Apr. 3, 1917.

Application filed June 2, 1916. Serial No. 101,854.

To all whom it may concern:

Be it known that I, ATHERTON D. CONVERSE, a citizen of the United States of America, and a resident of Winchendon, in the county of Worcester and Commonwealth of Massachusetts, have invented certain new and useful Improvements in Methods of Making Heads for Drums and other Musical Instruments, of which the following is a specification.

This invention relates to the methods of making drum heads.

The object of the invention is the production of a toy drum which may be manufactured at reduced cost and which will have greater rigidity than the drums now in general use.

The invention consists in providing each head with a cup-shaped portion adapted to fit over the barrel of a drum and securing to the cylindrical flange formed thereon, an outwardly extending tuck hoop such as a cord, against which the stay hoop fitted over said peripheral flange is adapted to be positioned.

The invention further consists in certain novel features of construction and arrangement of parts which will be fully understood by reference to the description of the drawings and to the claims hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized and that the invention is not limited to the precise arrangement and organization of these instrumentalities as herein shown and described.

Of the drawings:

Figure 1 represents a vertical section of a drum embodying the principles of the present invention.

Fig. 2 represents a plan of a head thereof.

Fig. 3 represents a plan of the head with the truck hoop or cord secured thereto.

Fig. 4 represents a section on line 4—4 on Fig. 3.

Fig. 5 represents a vertical section of the

dies used for forming a cylindrical depression in the head, a head being shown in section therein after the completion of the stamping operation, and

55

Fig. 6 represents a section showing the cup-shaped head positioned in a stay hoop preparatory to being positioned over the end of the barrel of the drum.

Similar characters designate like parts 60 throughout the several figures of the drawings.

In the drawings, 10 is a metal barrel having its ends turned inwardly as at 11 to form a rounded inwardly extending flange, 65 preferably cylindrical in cross section, as shown in the drawings. Over each end of the barrel 10 is a cup-shaped head 12 of skin, tough paper, or any similar material having a cord 13 secured to the cylindrical 70 portion thereof adjacent to the edge. This cord is preferably formed of twisted fiber, as indicated in Fig. 3 of the drawings, said fiber preferably being of the same material and color as the material from which the 75 cup-shaped head 12 is formed.

The cord of twisted fiber is secured to the head 12 by means of a row of stitches 14. This cord extending outwardly from the peripheral portion of the head 12 forms a 80 shoulder against which rests the inner ends of the stay hoops 15. These stay hoops 15 are preferably formed of metal with their opposite edges turned inwardly and inclosing a reinforcing member 16 of pasteboard 85 or some similar material. The inwardly extending edges are preferably curved as shown in Figs. 1 and 6 of the drawings. Each stay hoop 15 is provided with a plurality of openings 17 therethrough adapted 90 to receive the cords 18 by which the stay hoops may be drawn toward each other in the usual manner, thereby causing the heads 12 to be firmly stretched over the rounded edges of the flanges 11 at either end of the 95 barrel 10.

In making the heads 12 a circular blank 19 is cut out, as indicated in Fig. 3 of the drawings, and then by means of a row of stitches 14 the cord 13 of twisted fiber is 100 secured to one face thereof adjacent to the edge of said blank, all as shown in Figs. 3

and 4 of the drawings. The blank 19 with the cord 13 secured to one face thereof is then placed cord side down upon a die plate 20 and subjected to pressure of a male die 21 which causes a depression to be formed in the center of the head 12, as indicated in Fig. 5 of the drawings. When thus shaped, the head 12 is adapted to be fitted over the end of the barrel 10.

10 Each head when thus formed into a cup-shape with the cords 13 extending outwardly from the periphery of the cylindrical portion thereof, is placed upon a stay hoop 15, as indicated in Fig. 6 of the drawings, the 15 cord or tuck hoop 13 resting upon the upper edge of each stay hoop 15. The diameter of the depression 22 in each head 12 is the same as the diameter of the barrel 10, and each head supported by the stay hoop 15 is then 20 placed over an end of the barrel 10. The securing cords 18 are then inserted through the various openings 17, and when the stay hoops 15 have been drawn sufficiently toward each other to give the required stretch 25 to the heads 12, the cords are secured in position in any well-known manner.

By making the tuck hoop 13 of twisted fiber, it has the appearance of a skin such as is usually used in the head of a drum. By 30 means of this construction a great saving in material is made, for in the construction of the drum heretofore, the head must be of much greater diameter so that its edges may be tucked in around the tuck hoop. 35 By constructing the drum in the manner herein described, the twisted fiber cord secured to the edges of the head form the tuck hoop, and in a small sized drum there is a saving of at least two inches in the diameter of the blank used to form the head. Obviously this saving in material is of great 40 advantage.

Moreover, in the manufacture of toy drums where fiber is used in the construction of the drum heads, it has been very difficult to fit the heads over the barrel, the material not having sufficient stretch to permit the head to be drawn over the opposite ends of the barrel. As a consequence, the 50 tendency has always been for the stay hoop to rest substantially on the top of the head, and this permits it to be easily displaced, which is a great objection.

One of the main objects of this invention 55 is to obviate this difficulty and provide a means whereby the head may be pulled down over the end of the barrel of the drum, and thereby permit a considerable portion of the stay hoop to also be pulled 60 down over the end of the barrel, as shown in Fig. 1 of the drawings. By means of this construction the entire drum is greatly strengthened.

Heretofore in the manufacture of drums, 65 in order to stretch the head over the end of

the barrel, it was necessary to wet the head. When the head while in this condition was pulled down over the edge of the barrel, it was very liable to wear the head thin in spots, especially if there was any rough portion or other obstruction on the edge of the barrel where the head was drawn over.

70 By subjecting the blank from which the head is manufactured to pressure and forming it into the cup-shape prior to its being 75 positioned over the end of the barrel, these objections have been entirely overcome.

By providing inwardly projecting curved flanges at each end of the barrel 10, all danger of injuring the head when in position is 80 prevented.

Heretofore, in the manufacture of toy drums, skilled operators were required to pull the edges of the head around the tuck hoop and secure said edges in position. By 85 means of the method herein described, this operation of tucking the edges of the head around the tuck hoop will be entirely eliminated, making the entire method of forming the drum much cheaper than the manufac- 90 ture of the drum in the old way.

Not only is the present method much cheaper than the method heretofore used, but the head and the stay hoop may be formed entirely by machinery, and a much 95 more perfect article produced.

The present method is made possible on account of the ability to use metal hoops, as heretofore when the wooden hoops were used, these would vary in size and also in shape, 100 and as a consequence it would be almost impossible to manufacture the heads in the manner herein described.

Owing to the variation in the size and shape of wooden hoops the heads would not 105 accurately fit the hoops, and consequently in the former method of constructing drums it would always be necessary to fit each tuck hoop and head to the stay hoop.

In the present method of manufacturing 110 these drums, all of these objections have been entirely obviated. Heretofore, in the manufacture of the barrels of drums, it has been the usual practice to crimp the edges at right angles on a hand machine or nail a 115 wooden hoop around the inside of the opposite ends of the barrel, said wooden hoop projecting above the metal barrel.

Both of these methods have been found in practice to give imperfect results, as it is 120 impossible to secure thereby a perfectly cylindrical barrel.

By making the ends of the barrel with an inwardly curved flange substantially cylindrical in cross section, it is possible to 125 secure a perfectly cylindrical barrel, while the inwardly extending flange formed at either end thereof strengthens the barrel and retains it in its cylindrical form even under considerable pressure.

Another advantage of constructing the barrel in this manner is that the curved edges at either end of the barrel give a good bearing surface over which the head may be 5 turned in the process of tightening.

Heretofore in the construction of these toy drums, it was necessary to draw the head over a square corner which made the tightening of the head very difficult, and afforded 10 considerable opportunity for injury to said head.

It is believed that the many advantages of this invention will be fully understood from the foregoing description.

Having thus described my invention, I claim:

1. The method of making heads for drums and other musical instruments which consists in taking a circular disk of thin fibrous 20 drum head material, and sewing a cord to one face thereof adjacent the edge.

2. The method of making heads for drums and other musical instruments which consists in taking a circular disk of thin fibrous 25 drum head material, and sewing a cord of

twisted fiber to one face thereof adjacent the edge.

3. The method of making heads for drums and other musical instruments which consists in taking a circular disk of thin fibrous 30 drum head material, sewing a cord to one face thereof adjacent the edge, and forming said disk under pressure into a cup-shape.

4. The method of making heads for drums 35 and other musical instruments which consists in taking a circular disk of thin fibrous drumhead material; securing a projecting member to one face and adjacent the edge thereof; and then forming said disk into a 40 cup-shape with said projecting member on the periphery of the cylindrical portion thereof.

Signed by me at Winchendon, Mass., Worcester county this 27 day of May, 1916. 45

ATHERTON D. CONVERSE.
